UNITED STATES PATENT OFFICE

JOHN H. DOMKEE, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

SILDE BUCKLE

Application filed January 29, 1931. Serial No. 512,087.

This invention relates to slide buckles used for adjusting the length of looped straps, webbing, or the like, threaded therein without penetrating the material, and especially to that class of slide buckles of which the frame and the intermediate bar structure are made from a single piece of wire, and the objects of the invention are to provide an indestructible slide buckle; and to provide a slide buckle of the pair of loops type, connected at one side and free at the opposite side, with a securing member adapted to relatively secure the loops at their free side. With these and other objects in view, as may become apparent from the within disclosures, the invention consists not only of the particular form herein pointed out and illustrated in the drawings, but readily admits of certain modifications within the scope of what hereinafter may be claimed.

The character of the invention may be best understood by the reference to one illustrative device embodying the invention and illustrated by the accompanying drawings in which the Figure 1 is an upright elevation of the device; the Figure 2 is a cross-section on the line "2-2" in the previous figure; and the Figure 3 is a fragmentary front elevation of one of the side structures of the device and illustrating a securing member in a relative position therewith to be folded around two right angled portions thereof.

The device about to be described is an improvement upon a slide buckle structure well known in the art and which is made from a single piece of wire bent to provide a pair of loops integrally connected at one side and free at the opposite side. Such a structure is easily distorted or destroyed by means of pulling apart the loops at their free side. The applicant in a previous application filed December 13, 1929, Serial Number 413,864, therein disclosed a slide buckle structure of the pair of loops type of which the engaging metals of the free side of the loops are united

in permanent intimate union as are also the engaging metals of the wire extremities and a side structure, the securing means therein including by inference the extraneous element of heat necessary to amalgamate the engaging metals. The novelty herein disclosed however resides in a securing means provided by and mounted upon the pair of loops and comprising a sheet-metal member having portions adapted to be folded around adjacent parts of wire structure that are at an angle, one to the other.

As illustrated, the device is chiefly made of wire a middle portion of which is bent to form the pair of loops 1 and 2 in a common plane, each of said loops having an open and unobstructed interior area, and both of said loops being integrally connected by means of the side structure 3, but free at the opposite side, the wire ends 4 and 5 extending integrally from the free side of the loops 1 and 2, across the slide buckle and in planes parallel one to the other but perpendicular to the free sides of the loops 1 and 2, the wire extremities 6 and 7 engaging the side structure 3 that the wire ends 4 and 5 may thus complete the loops 1 and 2 which together provide the upper horizontal bar 8, the lower horizontal bar 9, the connected side structure 3, and the side structure portions 10 and 11, the wire ends 4 and 5 together providing the slide buckle with a horizontal intermediate bar structure. The sheet-metal member 12 may be made in any convenient form to serve the purpose about to be explained, but as illustrated it is stamped out in substantially rectangular form having the marginal recess 12-A and the marginally open slots 12-B and 12-C in longitudinally aligned relation, one with the other, thus adapting the recessed portion of the member 12 for folding, on the dotted lines 12-D and 12-E (illustrated by the Figure 3) around a part of each of the side structure portions 10 and 11 or, as used upon the op-

posite side of the slide buckle, around the side structure 3, while the other portion of the securing member is adapted to be folded along the dotted lines 12—F, 12—G, 12—H, 5 and 12—I (also illustrated by the Figure 3) around adjacent parts of the wire ends 4 and 5, or the extremities 6 and 7 as illustrated by the Figures 1 and 2, the loops 1 and 2 thus being securely connected at their otherwise 10 free side by means of a securing member 12, and the extremities 6 and 7 being securely connected with the side structure 3 also by means of a securing member 12. The slide buckle, thus having its parts relatively secured in the manner described, thereby becomes practically indestructible by wanton manipulation or by use.

I claim:—

1. A slide buckle comprising a piece of 20 wire of which a middle portion is bent to form in a common plane a pair of loops integrally connected at one side and free at the opposite side, each of the wire end portions forming a part of one of said loops and both 25 of the said wire end portions extending from the said free side in planes parallel one to the other and perpendicular to the free sides of the loops to engage their extremities with the connected side, a sheet-metal securing 30 member securing the loops one to the other at the said free side, and a similar securing member also provided by the loops to secure the engaging extremities of the wire to the said integrally connected side.
35. 2. A slide buckle comprising a piece of wire of which a middle portion is bent to form in a common plane a pair of loops integrally connected at one side structure and free at the opposite side structure, each of 40 the wire end portions forming a part of one of said loops and both of said wire end portions extending from the said free side in planes parallel one to the other and perpendicular to the free sides of the loops to en- 45 gage their extremities with the said connected side, means provided by both loops to relatively secure the loops one to the other at the said free side, and similar means also provided by the loops to secure the engaging 50 wire extremities to the said integrally connected side, each of said securing means comprising a sheet-metal member of which a portion is adapted to be folded around a side structure and an integral portion of said 55 member being adapted to be folded around adjacent structure which is at right angles to said side structure.
60. 3. A slide buckle comprising a piece of wire of which a middle portion is bent to form in a common plane a pair of loops, each loop having an open and unobstructed interior area, and both loops being integrally connected at one side and free at the opposite side permitting the separation of one 65 loop from the other along said plane, each

of the wire end portions forming a part of one of the loops and both of said wire end portions extending together from said free side in planes parallel one to the other and perpendicular to the free side of the loops 70 to engage their extremities with the connected side, and a securing sheet-metal member mountable upon both loops at their free sides to relatively secure the pair of loops against said separation.
